Primary Examiner — Cathron Brooks*Assistant Examiner* — Christian P McLean(74) *Attorney, Agent, or Firm* — Banner & Witcoff, Ltd.(57) **CLAIM**

The ornamental design for a display screen with graphical user interface, as shown and described.

DESCRIPTION

The FIGURE is a front view of a display screen with graphical user interface showing our new design.

The outermost broken lines illustrate the display screen, and the remaining broken lines illustrate portions of the graphical user interface. None of the broken lines form part of the claimed design.

1 Claim, 1 Drawing Sheet(56)
